CLAIM

The ornamental design for a vertical transaction card, as shown and described.

DESCRIPTION

The patent or application file contains at least one drawing executed in color. Copies of this patent or patent application publication with color drawing(s) will be provided by the Office upon request and payment of the necessary fee. Color is an aspect of the front and back of the vertical transaction cards of the present design as shown in FIGS. 1 and 2.

FIG. 1 is a front elevational view of the vertical transaction card showing my new design;

FIG. 2 is a rear elevational view thereof;

FIG. 3 is a left-side elevational view of FIG. 1, the right-side elevational view being a mirror image thereof; and,

FIG. 4 is a bottom plan view of FIG. 1, the top plan view being a mirror image thereof.

The broken line showing portions of the vertical transaction card is included for the purpose of illustrating environmental structure and forms no part of the claimed design.
